PUNCHBOARD AMUSEMENT DEVICE

Donald Cook, Great Falls, Mont.

Application September 12, 1949, Serial No. 115,197

3 Claims. (Cl. 273—139)

1

This invention relates to an amusement device of the type which employs a replaceable punch board and makes automatic awards or discharges of articles other than those contained in the punch board itself, responsive to insertion of a punch or stylus in certain preselected perforations in the punch board.

I recognize that it has heretofore been known to provide such devices employing replaceable punch boards, however in these devices it has either been necessary to use punch boards of special construction or else to have special parts or elements associated with such punch boards to properly associate the award actuating mechanism therewith.

With the foregoing in mind, it is a primary object of my invention to provide such a device which utilizes a replaceable punch board of usual commercially available type, and which has the contact elements of its electrical award actuating mechanism removably associated directly therewith in various changeable positions, as desired, to the end that the closing of circuits through any of said contact elements will actuate the award or article delivery mechanism. Such an arrangement will obviously greatly simplify the construction and the economy of production of such devices.

A further object is to provide such a device utilizing a plurality of award or article holders, each electrically actuated to release its contents responsive to insertion of the punch or stylus in a particular preselected perforation in the punch board and thereafter to remain in released position until manually reset, to the end that repeated insertions of the punch into a prize winning perforation will not result in repeated awards.

Still further objects are: to provide a novel means for causing the article or award holders to discharge their contents responsive to energizing of their respective circuits; and, to provide an article discharge chute arranged to deliver to the exterior of the device any articles punched from the perforations in the punch board as well as those discharged from the article holders.

In this application I show and describe only the preferred embodiment of my invention, simply by way of illustration of the practice of my invention as by law required, together with but a single modification thereof. However I recognize that my invention is capable of other and different embodiments and that the several details thereof may be modified in various ways, all without departing from my said invention.

2

Accordingly, the drawings and description herein are to be considered as merely illustrative and not as exclusive.

In the accompanying drawings:

5 Figure 1 represents a perspective view of an amusement device embodying the preferred form of the invention;

10 Figure 2, an enlarged section on the line 2—2 of Figure 1, looking in the direction of the arrows;

Figure 3, an enlarged cross-section, partly broken away, on the line 3—3 of Figure 1, looking in the direction of the arrows; and,

15 Figure 4, an enlarged fragmentary section on the same plane as Figure 2, showing a slightly modified form of the invention.

20 Referring now in detail to the accompanying drawings, the reference character C therein designates a housing or cabinet which may be of usual material such as wood. The rear panel or back of the cabinet preferably is in the form of a door 1, hinged to the cabinet as shown to permit access to the interior thereof for servicing and repairs, and suitable means such as a 25 padlock 13 is provided for preventing access to the cabinet interior by unauthorized persons.

The front panel or face 2 of the cabinet is formed with a rectangular opening 3 therethrough in which is removably disposed a usual punch board 4 having a plurality of suitably disposed perforations or bores 5 therethrough in usual manner. Small articles of merchandise or small rolls or wads of paper bearing suitable printed matter, these being designated generally by the reference character 6, may be disposed in some of these perforations 5, while electrical contact members which may be in the form of small screws 7 may be inserted or threaded into others of said perforations from the rear face of the punch board 4. If desired, the front face of the punch board 4 may be masked by a sheet of punchable paper 8 pasted or held thereover as usual to make impossible the visual ascertainment of the contents of the various perforations, the paper 8 preferably having indicia thereon in registry with the various perforations, as in Figure 1, to indicate the entrances thereto.

50 Any suitable means may be provided for removably mounting the punch board 4 in the cabinet opening 3, the preferred means comprising a rectangular marginal frame 9 fixedly secured around the opening and overlapping the edges thereof on the exterior face of the cabinet front 1, and another rectangular frame 10 similarly related to the opening 3 interiorly of the

cabinet, the interior frame 10 being removably secured against the rear or interior face of the front 1, as by usual wood screws 11. Thus the punch board 4 will be sandwiched between the two frames 9 and 10 and removable only through the interior of the cabinet C by authorized persons.

For use in conjunction with the punch board 4 in usual manner, there is provided a punch 27 having an operative blade or portion of conducting material adapted for insertion into the various perforations 5 in usual manner through the paper 8, where such is employed, either to expel the articles 6 rearwardly from said perforations or to engage the contact members 7 disposed in various of said holes and close electrical circuits which include said punch and contact members as hereinafter described.

Positioned in the cabinet C at any suitable location above the bottom thereof are one or more movable article or award holders 14, each of suitable size and conformation to hold small articles or merchandise, money, printed matter and the like. Each of these holders or containers 14 is disposed for movement in any suitable manner whereby it will normally tend to assume a position which will cause its contents to be expelled or discharged by gravity, but is capable of assuming and being retained in a position which will cause its contents to be retained therein.

In the preferred embodiment of the invention there is provided a plurality of relatively aligned holders 14 which are each pivotally suspended from the under surface of the cabinet top, as by hinges 15, for movement about the horizontal axes defined by the pintles 16 of these hinges. Each of these holders is semi-cylindrical in shape, being formed of conducting metal, and opens upwardly when in the closed or article retaining position shown in full lines in Figure 2. However the hinge connection of each such holder is disposed at one side thereof eccentric to its center of gravity so that under the influence of gravity each such holder will normally tend to assume a downwardly swung or depending article discharging position, as indicated in dotted lines in Figure 2.

At its free end each such holder 14 carries a catch 17, preferably of resilient conducting metal terminating in a downwardly opening hook 18 to cooperate with the latch or retainer means for said holder.

In order to retain the several holders 14 in their upwardly swung or article retaining position, I provide in association with each such holder an electrically releasable latch means which may assume various forms considering the invention from its broader aspects, as will be apparent to those skilled in the art.

However, I prefer to utilize the form of latch means 19 illustrated in Figures 1 to 3 of the drawings, which means is in itself novel, extremely simple and economical, and permits the device of the invention to be readily reset by unskilled persons.

Such means comprises a link 19 of usual fusible metal which provides a mechanical and electrical connection between the holder catch 17 and a fixed conductor element which preferably consists of a metal hook 20 carried by a conductor bar 21, the latter being secured to the under surface of the cabinet top and extending parallel to the row of holders 14. By reference to the drawings it will be seen that when the holders 14 are swung upwardly to article retaining position

against the top of the cabinet, separate fusible links 19 placed under tension between each of the catches 17 and its associated hook 20, will retain said holders in position against the action of gravity.

The energizing of said respective latch means 19 is accomplished through a series of separate electrical circuits, each including one of said fusible links 19, said punch 27 and one of the contact members 7 in the punch board 4, so that engagement of any one of said contact members 7 by the punch 27 will close the particular circuit which includes said contact member and its associated fusible link 19. This will of course result in fusing or melting said link so that it will release its particular holder 14, allowing same to swing downwardly and discharge its contents.

Thus, as clearly shown in Figure 2, the device may be electrically connected to any suitable source of electricity, as through a usual two wire electric cord 22 having a usual plug 23 for insertion in a usual electric socket, as indicated in Figure 1. One branch or wire 24 of said cord is electrically connected to the conductor bar 21, as shown, thus it will be seen that the several hooks 20, fusible links 19 and holders 14 are connected in parallel with this wire 24. Each of the holders 14 in turn is electrically connected as by a flexible wire 25 to one of the contact members 7 in the punch board. The other branch or wire 26 of the cord is connected to the electrically conducting operative portion or blade of the punch 27, so that insertion of the punch into the various punch board perforations 5 in usual manner will either expel the articles 6 rearwardly from said perforations or cause the punch 27 to engage the contact members 7 disposed in some of the perforations. Obviously insertion of the punch into a perforation containing a contact member 7 with resultant engagement therewith will close the circuit through said members and their respective holder 14 and fusible link 19, causing the latter to melt and release the holder to article discharging position. It will be noted of course that the handle of the punch 27 is insulated from the blade or operative portion thereof, as by a covering of insulating material as shown, in order to prevent electric shock to users of the device.

The bottom of the cabinet C is defined by a sloping discharge chute 28 which extends beneath all of the holders 14 and the punch board 4, through a discharge opening 29 in the cabinet front to discharge articles received thereon which have been ejected either from the holders 14 or from the punch board perforations 5. Thus the single discharge chute 28 is operatively associated with both the holders and the punch board in a manner which contributes to the economy of construction and utility of the device. It will be noted that the dimensions of the discharge opening 29 are such as will prevent manual access therethrough to the article holders 14 and their associated mechanism aforementioned.

In the use of the device, which is believed to be obvious from the foregoing description, any desired articles of merchandise, printed matter, prizes and the like may be placed in the several holders 14, access being had thereto through the rear door 2, whereupon links 19 will be disposed between the several catches 18 and hooks 20 to maintain said holders in article retaining position. The contact members 7 for each of these holders 14 will of course be threaded into various preselected perforations 5 in the punch board

after first ejecting the articles or usual paper rolls 6 therefrom. As thus arranged, the punch may be inserted into various of the holes or perforations from the front of the board 4 to either eject the articles 6 therefrom, in the manner indicated in Figure 2, or to establish contact with the contact members 7 in said pre-selected perforations and discharge the contents of their respective holders 14, both the articles 6 and the contents of the holders 14 being received on the chute 28 and being delivered to the exterior of the cabinet through the discharge opening 29.

In one of the contemplated uses for my invention, same may be advantageously employed as a party amusement device, in which event the various perforations 5 of the punch board will be loaded with slips or rolls of paper 6 on which are printed instructions relative to the performance of stunts by those discharging said slips. The holders 14 also will contain similar slips of paper on which will be printed or written instructions for additional stunts, these preferably being the outstanding or highlight stunts. With this arrangement, the party guests may take turns operating the device and performing the respective stunts directed thereby, to the end that considerable amusement will be furnished.

Obviously, after the contents of the holders 14 are discharged, same may be reloaded, and the punch board 4 may be replaced by a new one as required, in which event the contact members 7 will preferably be placed in new or different perforations 5 to prevent users from becoming familiar with their locations.

In Figure 4 of the drawings I have illustrated a modified form and arrangement of electrically releasable latch means for each of the several holders 14, each said latch means comprising a fixedly positioned solenoid 18' which when energized receives direct current through one branch 24 of the electrical cord, the current passing through said solenoid and being conducted therefrom to one of the contact members 7 by the wire 25 as shown. A movable solenoid core or plunger 18a projects from one end of the solenoid to be disposed beneath the catch 17' of the holder 14 and support same in raised or article retaining position prior to energization of the solenoid. The punch 12 is connected to the other branch or wire 26 of the cord as in the preferred embodiment, so that engagement between the punch and contact member 7 will retract the core 18a into the solenoid 18' and out of latching engagement with the catch 17', thereby releasing the holder and permitting same to swing downwardly to article discharging position as heretofore described.

Having thus described my invention, I claim:

1. An amusement device comprising a hollow cabinet having an opening through one wall thereof, a punch board replaceably disposed in said opening and having a plurality of perforations therethrough, electrical contact members being removably disposed in certain of said perforations, a punch of electrically conducting material adapted for insertion in said perforations, a plurality of article holders of conducting material disposed in said cabinet for movement by gravity from a raised upright position to a tilted article discharging position, a main conducting bar extending adjacent said respective holders, and fusible links of electrical conducting ma-

terial connecting said holders to said conductor bar to normally maintain the holders in raised upright article holding position, means electrically connecting each of said article holders to one of said contact members, and flexible means electrically connecting said punch in circuit with said conductor bar, whereby engagement between said punch and one of said contact members will close a circuit through the fusible link and holder associated with that particular contact member, in combination with a sloping discharge chute extending beneath said holders and said punch board to the exterior of said cabinet.

2. An amusement device comprising a hollow cabinet having an opening through one wall thereof, a punch board of electrical insulating material replaceably disposed in said opening and having a plurality of perforations therethrough, electrical contact members being removably disposed in certain of said perforations, a punch of electrically conducting material adapted for insertion in said perforations, a plurality of article holders of conducting material disposed in said cabinet for movement by gravity from a raised upright position to a tilted article discharging position, a conducting element extending adjacent said respective holders, and fusible links of electrical conducting material connecting said holders to said element to maintain said holders in raised upright position, means electrically connecting each of said article holders to one of said contact members, and electrical means electrically connecting said punch in circuit with said conducting element, whereby engagement between said punch and one of said contact members will close a circuit through the fusible link and holder associated with that particular contact member.

3. An amusement device comprising a cabinet, a punch board of electrical insulating material replaceably supported by said cabinet and having a plurality of perforations therethrough, electrical contact members being disposed in certain of said perforations, a punch of electrically conducting material adapted for insertion in said perforations, an article holder disposed in said cabinet for movement by gravity from a raised upright article holding position to a tilted article discharging position, a stationary conducting element disposed adjacent said holder, a fusible link of electrical conducting material connecting said holder to said element to maintain the holder in raised upright article holding position, means electrically connecting said fusible link in circuit with said contact member, and means electrically connecting said punch in circuit with said conducting element, whereby engagement between said punch and said contact member will close the circuit through said fusible link.

DONALD COOK.
